UNITED STATES PATENT OFFICE

SIDNEY DORFMAN, OF BRONX, NEW YORK

FABRIC FEEDER FOR STRETCHING MACHINES WITH PRELIMINARY STRETCHING

Application filed June 21, 1928. Serial No. 287,223.

This invention relates to improvements in fabric stretching machines, particularly to a feeder for such machines and it is the principal object of my invention to provide a feeder 5 of this nature which may be used in any desired number as an attachment to fabric stretching machines, and which acts simultaneously as an auxiliary or preliminary stretcher for the fabric during feeding the 10 same to the main stretching machine.

Another object of my invention is the provision of a feeder for fabric stretching machines of a simple and comparatively inexpensive construction, yet durable and efficient 15 in its operation.

A further object of my invention is the provision of an attachment of this nature for fabric stretching machines which can be readily installed in any of the existing 20 machines without requiring material changes in their construction.

These and other objects and advantages of my invention will become more fully known as the description thereof proceeds 25 and will then be specifically defined in the appended claims.

In the accompanying drawings forming a material part of this disclosure:

Figure 1 is a plan view of a feeder and preliminary stretcher for fabric stretching machines constructed according to my invention. 30

Figure 2 is a side elevation thereof. 35

Figure 3 is a cross-section on line 3—3 of Figure 2.

Figure 4 is a cross-section on line 4—4 of Figure 2.

As illustrated my novel and improved 40 feeder consists of a base plate or bed 10 on which a bracket 11 is mounted, near one end thereof having a horizontally disposed arm 12 serving as guide for a comparatively short vertical shaft 13 carrying a sprocket wheel 14 over which a chain is guided by means of which the shaft 13 can be rotated from any source of power in a well known customary manner.

The lower end of shaft 13 carries a bevel 50 gear 15 in mesh with a bevel gear 16 on a

horizontal stub shaft 17 journalled in a block 18 on the base.

In close proximity to and in front of block 18 shaft 17 carries a gear 19 in mesh with a gear 20 on a shaft journalled also in block 55 18. The bevel gear 15 on shaft 13 meshes also with a bevel gear 21 on a shaft carrying a cam 22 adapted to engage a cam plate 23 suspended from bolts 24, 25 projecting from the side face of a fork-member 26 and 60 adapted to travel with their reduced ends in elongated slots 27, 28 of the cam plate 23 and to be held in adjusted position by means of nuts 29, 30.

The shaft 31 of bevel gear 21 and cam 22 65 carries also on the outside a disk 32 to which eccentrically the rod 33 is secured the other end is movably attached to a shaft 34 projecting laterally from a block or plate 35 supporting one end of the fork member 26. 70 The inner end of the fork member 26 carries an arm 36 having its end angularly downwardly bent, as at 37, and secured to the upper member 38 of a feeder, the lower face of which is serrated, as at 39 and adapted to co-operate 75 with the upper serrated face 40 of another member 41 fastened to an arm 42 extending from the lower end of block or plate 35.

A strong spiral spring 43 is attached at its upper end to a screw in the side face of 80 arm 36 while its lower end is secured to a screw in the side face of arm 42 and the spring has a tendency to draw both feeder members 38 and 41 normally together, but allowing a separation as and for a purpose later to be 85 described.

In juxtaposition to the mechanism described so far, the bed 10 carries also bearings 44 for a lower feed roller 45, with which co-operates an upper feed roller 46 on a shaft 47 90 journalled at its inner end in a bearing block 48 hingedly secured, as at 49 to a transverse block 50 on the bed 10. The block 50 has up-standing side walls 51 which are provided near their upper ends with arcuate slots 52 95 in which pins 53 projecting from the side of bearing block 48 are guided with a certain play allowing a raising and lowering of the upper roller and its bearing block 48 from and against the lower roller 45. The bear- 100

ing 54 of the shaft 47 of the upper roller 46 supports one end of a rod 55, the other end of which is supported in the upper part of block 48.

5. A fabric guide 56 is rotatably secured by means of the lower perforated ends of its side bars 57, 58 to rod 55 so as to swing about the same to engage or release the fabric fed between rollers 45, 46 to the fabric stretching machine.

10. The shaft 47 for the upper roller 46 carries at its inner end a gear 59 in mesh with a gear 60 on the shaft for the lower roller 45 and in juxtaposition to said gear 60 its shaft carries also a gear 61 in mesh with an intermediate gear 62 on a shaft 63 which meshes with gear 19 on shaft 17.

15. The operation of my apparatus will be quite clear from the above description and 20 by inspection of the accompanying drawings.

25. Upon the rotation of shaft 13 by any source of power, the rotation of the bevel gears will bring the cam 22 into engagement with the cam face 64 of cam plate 23, and elevate arm 36 and the upper feed member 38 to allow the insertion of the fabric, the end of which is then guided between rollers 45 and 46 and will during the rotation of these rollers by the intermediary of the gear system 30 be fed to the stretching machine while guide 56 will keep the fabric issuing from between the rollers against rumpling and wrinkling.

35. It will be clear that the fabric during its feeding between the serrated faces of members 38 and 41 and between rollers 45 and 46 will receive a preliminary stretching.

40. It will be understood that I have shown and described as an example of the many possible ways to practically construct my apparatus, its preferred form only, and that I may make such changes in its construction as come within the scope of the appended claims without departure from the spirit of my invention and the principles involved.

45. Having thus described my invention, what I claim as new and desire to secure by Letters Patent is:

1. Feeder attachment for fabric stretching machines, comprising a pair of co-operating 50 gripping members having oppositely disposed serrated gripping faces, arms to which said gripping members are secured, a means for normally holding said serrated faces in engagement, and means for automatically closing said gripping faces, over a piece of fabric, operating means therefor, a pair of rollers adapted to be operated from said operating means to feed the fabric from between said gripping members to the fabric stretching machine.

55. 2. Feeder attachment for fabric stretching machines comprising a plurality of co-operating fabric gripping means, a pair of arms to which said gripping means are attached 60 in spaced relation to each other, a spring for

normally closing said gripping means over a piece of fabric between them, a revolving vertical shaft, a means actuated from said shaft to operate said arms, a pair of feed rollers adapted to be manually separated from each other and operated from said means actuated by said shaft to feed the fabric from between said gripping means to the stretching machine, and a means combined with said rollers to keep the fabric smooth.

70. 3. In a feeder attachment for fabric stretching machines a vertical revolving shaft, a bevel gear thereon, a plurality of bevel gears in mesh with said shaft operated bevel gear, shafts for said bevel gears, a cam on one of said shafts, a cam-plate, a pair of arms connected at one end, a pair of fabric grippers at the opposite separated ends of said arm, said cam-plate movably attached to said arms, a disk juxtaposed to said cam, a connecting rod attached to said disk and to the connection of said arms, for operating said grippers to feed a piece of fabric, a spring for normally holding said grippers in engagement over a piece of fabric, and a means operated from said gripper operating means for feeding the fabric from said grippers to a fabric stretching machine.

75. 4. In a fabric feeder attachment for stretching machines, a bed, a lug on said bed, a block hinged to said lug, a pair of superposed rollers, shafts therefor, the upper of said shafts journaled in said block and the lower in said lug, a rod spaced from said upper roller and parallel thereto, and a weighted frame rotatably attached to said rod for smoothing the fabric fed by said rollers to the stretching machine.

80. 5. A fabric feeder attachment for stretching machines comprising a bed, a bracket mounted thereon, a horizontally disposed arm on said bracket, a short vertical shaft guided through said arm, a sprocket wheel on said shaft adapted to be revolved from a source of power, a bevel gear on the lower end of said shaft, a horizontal shaft, bevel gears on the ends of said horizontal shaft in mesh with said bevel gear on the lower end of said vertical shaft, a horizontal shaft angularly disposed to said first named horizontal shaft, a bevel gear on said shaft in mesh with the bevel gear on said vertical shaft, a train of gears operated from said last named bevel gear and its shaft gripping means adapted to be operated from said vertical shaft and bevel gears, and a pair of rollers adapted to be operated from said train of gears for rotation to feed a piece of fabric to the stretcher.

85. 6. A fabric feeding attachment for stretching machines, comprising a bed, a bracket mounted thereon, a vertical revolving shaft held by said bracket, a train of bevel gears adapted to be operated from said shaft, a pair of grippers, a fork member therefor, cam means for operating said grippers to grip over 90

and release the fabric, a spring for normally keeping the parts of said arms and said grippers in engagement over a piece of fabric but allowing a separation, and a pair of separable rollers to which said fabric is fed from the grippers, a train of gears adapted to be operated from said train of bevel gears to operate said rollers to feed the fabric from between said grippers to the stretching machine, and a weighted frame associating with said rollers to keep the fabric smooth during its feeding operation.

Signed at New York, in the county of New York and State of New York this 20th day
15 of June, A. D. 1928.

SIDNEY DORFMAN.
